UNITED STATES PATENT OFFICE.

HOSEA K. KRIEBEL, OF PHILADELPHIA, PENNSYLVANIA.

FURNACE FOR BURNING COMMINUTED MATERIAL.

No. 820,932.

Specification of Letters Patent.

Patented May 15, 1906.

Application filed December 29, 1904. Serial No. 238,757.

To all whom it may concern:

Be it known that I, HOSEA K. KRIEBEL, a citizen of the United States, residing in the city of Philadelphia, in the county of Philadelphia and State of Pennsylvania, have invented certain new and useful Improvements in Furnaces for Burning Comminuted Materials, whereof the following is a specification.

10 It is one object of the present invention to provide a combined furnace and boiler for generating a high percentage of power by exposing to the heated products of combustion a great amount of heating-surface.

15 Another object is to provide such a furnace with means for burning comminuted materials to attain these ends.

Other objects will appear hereinafter.

The invention consists of the improvements hereinafter described and finally claimed.

20 The nature, characteristic features, and scope of the invention will be more fully understood from the following description, taken in connection with the accompanying drawings, forming part hereof, and in which—

Figure 1 is a sectional view of the combined boiler and furnace. Fig. 2 is a sectional view taken on the line 2 2 of Fig. 1; and 30 Figs. 3, 4, and 5 are sectional views illustrating a modified form of the invention.

The furnace may be constructed of any suitable material such as is well known in the manufacture of such apparatus.

35 In the drawings, *a* is a fire-brick structure, which may be inclosed in a metallic shell *b*. Surrounding this is a similar shell *c*. Located at the top of the furnace there is shown a sectional boiler *d*, although the style of the 40 boiler is immaterial to the invention. Extending downwardly from the boiler and partially encircling the furnace proper are a series of water chambers or compartments *e*.

e' is a compartment arranged at right angles to the chamber *e* and forming a connection therefor.

f is a fire-grate, and *g* designates a series of shelves or supports formed of fire-brick for the reception of the materials to be burned—50 such, for instance, as culm, peat, coal-screenings, &c.

h designates passages for the circulation of gases, which, as shown, pass between the various shelves and through the boiler to the 55 exhaust *h'*. Between the boiler *d* and the chamber *e'* there may traverse the passages *h*

the water-pipes *i* for increasing the heating-surface of the apparatus, although the pipes may be omitted, if desired. At the front of the furnace and hinged thereto are means of 6c obtaining access to the furnace. They are provided with air-compartments *j* and baffle-plates *j'* and suitable ventilators or draft-doors *k*, having communication with the furnace by means of ports or openings *l*. It 65 will be seen by reference to Fig. 2 that these openings are arranged immediately above the shelves or supports and also above the grate-bars.

In practice it has been demonstrated that 70 the draft produced by the arrangement is all that is necessary to the successful operation of the furnace and does away with forced drafts and drafts operating through the bottom of the furnace. The above-described 75

apparatus is calculated to burn materials such as culm, peat, coal-screenings, &c., and a description will now be given of the manner of burning the same. The fire is started upon the grate-bars, and when the shelf immediately above the said bars has become sufficiently heated to ignite the materials to be burned the same are introduced through the door opposite to said shelf, and when the shelf above has in turn become duly heated 85 the operation is repeated, and so on until the entire furnace is in operation.

In practice it has been shown that a long 90 interval (approximately twenty-four hours) elapses before the furnace will need attention other than, perhaps, regulating of the air ports through the parts *k*. After this long run of the furnace the ashes on the shelf immediately above the grate-bars are raked or pushed into the ash-pit and the contents of 95 the shelf immediately above are raked onto the shelf thus emptied, and so on upward until the top shelf is reached, when a new charge of material is introduced to said shelf.

In the modified forms shown in Figs. 2, 3, 100 and 4 the fire-brick shelves instead of being arched, as in Fig. 1, are shown as being straight across the furnace and having embedded therein a series of pipes *j'*, having communication with the water-chambers *e*. 105

As shown in Fig. 4, the ends of the pipes or tubes are bent in opposite directions, as at *j''*, to facilitate circulation.

The above-described type of combined furnace and boiler is at once economical as 110 well as efficient, and the great amount of heating-surfaces exposed to the products of

combustion insures an increased percentage of efficiency. This together with the fact that there is little or no smoke given off from the exhaust, due to the fact that the flames 5 consume the greater part of the same, and also for the reason that there is comparatively little ashes left in the pit, makes the apparatus commercially important. The furnace may either be used for generating 10 heat or power.

It will be obvious to those skilled in the art to which the invention appertains that modifications may be made in details without departing from the spirit thereof. Hence the 15 invention is not limited further than the prior state of the art may require.

Having thus described the nature and objects of the invention, what I claim as new, and desire to secure by Letters Patent, is—
20 A furnace for burning comminuted mate-

rials provided with a series of superposed communicating hearths that overlap to form a tortuous flue, a boiler, water-compartments almost wholly surrounding the furnace, laterally-arranged communicating means for 25 procuring a circulation of water across the furnace, means located beneath the lower hearth for heating the same to initially start the furnace and means opposite the hearths for introducing the materials to be burned 30 provided with doors equipped with ports for the admission of air arranged above the level of the respective hearths, substantially as described.

In testimony whereof I have hereunto set 35 my hand and seal—

HOSEA K. KRIEBEL. [L. S.]
